ANIMAL FIGURE TOY

Irvin J. Gershen, Springfield, N.J., assignor to Johnson & Johnson, a corporation of New Jersey

Filed Feb. 9, 1966, Ser. No. 970

Term of patent 14 years

(Cl. D34—15)

FIG. 1 is a front view of an animal figure toy showing my design;

FIG. 2 is a side view of an animal figure toy showing my design;

FIG. 3 is a front view thereof showing my design in an alternate position; and,

FIG. 4 is a top view of the animal figure toy shown in FIG. 1.

I claim:

The ornamental design for an animal figure toy, as shown.
